UNITED STATES PATENT OFFICE.

JAMES C. BROYLES, OF COLUMBUS, MISSISSIPPI.

CHOKE ATTACHMENT FOR GUN-BARRELS.

SPECIFICATION forming part of Letters Patent No. 653,613, dated July 10, 1900.

Application filed April 17, 1900. Serial No. 13,255. (No model.)

To all whom it may concern:

Be it known that I, JAMES C. BROYLES, a citizen of the United States, residing at Columbus, in the county of Lowndes and State 5 of Mississippi, have invented a new and useful Choke Attachment for Gun-Barrels, of which the following is a specification.

This invention relates to shotguns, and has for one object to provide an improved choke attachment therefor whereby the amount of taper at the muzzle of the gun-barrel may be conveniently adjusted to control the concentration and scattering of the discharged shot. It is furthermore designed to provide improved means for mounting the device upon the gun-barrel, so that it may be in convenient reach of the forward hand which grasps the gun-barrel in order that it may be operated without removing the gun from the shoulder, and finally to provide means for limiting the device to a plurality of predetermined adjustments.

With these and other objects in view the present invention consists in the combination 25 and arrangement of parts, as will be herein-after more fully described, shown in the accompanying drawings, and particularly pointed out in the appended claims, it being understood that changes in the form, proportion, 30 size, and minor details may be made within the scope of the claims without departing from the spirit or sacrificing any of the advantages of the invention.

In the drawings, Figure 1 is a side elevation 35 of a magazine-shotgun having the present invention applied thereto. Fig. 2 is an enlarged detail sectional view taken through the muzzle of the gun-barrel. Fig. 3 is a detail perspective view of the muzzle of the gun-barrel. Fig. 4 is a detail perspective view of the adjusting attachment. Fig. 5 is a detail perspective view of the cam-shaped stop for limiting the adjustment of the attachment.

Corresponding parts in the several figures 45 of the drawings are designated by like characters of reference.

Referring to the accompanying drawings, 1 designates any ordinary single-barrel magazine-shotgun having the usual magazine 2, 50 located longitudinally beneath the barrel 3. As best shown in Fig. 3 of the drawings, the muzzle of the barrel is slotted or provided

with a plurality of longitudinal incisions, thereby forming a plurality of substantially fine or thin spring-tongues 4, which are designed to be drawn inwardly to vary the diameter and the taper of the muzzle, and thereby adjust the degree of choke. 55

Slidable longitudinally upon the gun-barrel is a tube or sleeve 5, having the outer end 60 portion of its bore tapered, so that its smallest diameter is at the outer end of the sleeve, and by drawing the sleeve rearwardly or toward the stock of the gun the spring-tongues 4 will be drawn inwardly to increase the taper 65 of the bore of the gun-barrel at the muzzle thereof, and by moving the sleeve outwardly a reverse adjustment of the tongues and the bore of the gun will be had. It will of course be understood that the smallest diameter of 70 the bore of the sleeve will be substantially the same or a trifle greater than that of the gun-barrel, so that when the sleeve is at its outer limit and the spring-tongues assume their normal position the bore of the sleeve 75 may not interfere with the discharge of shot.

To conveniently operate the slideable sleeve, there is provided a pair of diametrically-opposite jaws 6, which are duplicates in form and are located at opposite sides of the gun-barrel. The forward end of each jaw is rigidly connected to the rear end of the sleeve by means of any suitable fastening 7 and is curved or bowed downwardly to fit between the magazine 2 and the gun-barrel, the rear 85 end of the jaw being bent inwardly to form a rounded finger-piece 8 for the convenient operation of the sleeve and to prevent injury to the fingers of the hand which operates the loading-slide 9, that is commonly mounted 90 upon the magazine. Intermediate of the opposite ends of the jaws there is a connecting cross-bar 9, which holds the jaws together and is slideable in the slot or space between the barrel and the magazine. 95

In order that the forward movement of the sleeve may be stopped at certain predetermined limits, there is provided a stop ring or collar 10, which is fitted to turn upon the forward end of the magazine and is held against 100 forward displacement by the flanged closure-plug 11, which is commonly provided for the forward end of the magazine. The rear edge 12 of this collar or ring is inclined, so as to

form a cam-face for engagement with the shoulder 13, formed integrally with the rear end of the sleeve, whereby the outward movement of the latter is limited. By turning the 5 stop-collar upon the magazine different points of the cam edge will be presented for engagement by the stop-shoulder on the sleeve, and thus a great variety of limitations may be provided for the sleeve. The rearward movement of the sleeve is limited by means of a 10 stop 14, which is located in the path of the rear end of the sleeve and the shoulder 13 and in the present application of the device is formed by the clip, which embraces both the 15 gun-barrel and the magazine to connect the latter to the former.

Although the present device has been shown and described as applied to a magazine-gun, wherein the magazine forms a support for the 20 stop ring or collar, yet it will be understood that any suitable longitudinally-disposed support may be employed.

From the foregoing description it will be apparent that the present invention provides 25 simple and efficient means for adjusting the choke of a gun-barrel, and the device may be readily applied to a gun without changing the latter beyond slitting the muzzle of the barrel, and the device is always in convenient 30 position for operation.

What is claimed is—

1. The combination with a gun-barrel, having a plurality of incisions at the muzzle thereof, of a tapered sleeve slidable upon the muzzle, and an operating finger-piece extending 35 rearwardly alongside of the barrel.

2. The combination with a gun-barrel having a plurality of longitudinal incisions at the muzzle thereof, of a tapered sleeve slidable 40 upon the muzzle, and a pair of opposite jaws extending rearwardly from the sleeve, located at opposite sides of the barrel, and forming a finger-piece for adjusting the sleeve.

3. The combination with a gun-barrel, having an exteriorly-smooth muzzle, provided 45 with a plurality of longitudinal incisions, of an interiorly-smooth sleeve, slidable upon the muzzle, and having a tapered bore, which decreases in diameter toward the outer end 50 thereof.

4. The combination with a gun-barrel having a plurality of longitudinal incisions in the muzzle thereof, of a tapered sleeve slidable upon the muzzle, and an adjustable stop 55 to limit the forward movement of the sleeve.

5. The combination with a gun-barrel having a plurality of longitudinal incisions in the muzzle thereof, of a tapered sleeve slidable upon the muzzle, and provided with a stop-shoulder, a support at one side of the barrel 60 and a rotatable stop mounted upon the support and for engagement by the stop-shoulder.

6. The combination with a gun-barrel having a plurality of longitudinal incisions in the muzzle thereof, of a tapered sleeve slidable 65 upon the muzzle, and provided with a stop-shoulder, a support at one side of the barrel, and a cam-shaped ring or collar, which is rotatable upon the support, and has its cam edge located in the path of the stop- 70 shoulder on the sleeve.

7. The combination with a shotgun, having a barrel which is provided with a plurality of longitudinal incisions in the muzzle thereof, and a longitudinal support spaced at one side 75 of the barrel, of a tapered sleeve slidable upon the muzzle of the barrel, a pair of opposite jaws connected to the rear or inner end of the sleeve, and having their opposite ends received between the support and the barrel, a 80 stop-shoulder provided upon the rear end of the sleeve, and a rotatable cam-shaped ring or collar mounted upon the support and having its cam-face located in the path of the stop-shoulder on the sleeve. 85

8. The combination with a gun-barrel having a plurality of longitudinal incisions in the muzzle thereof, and a longitudinal tubular magazine spaced at one side of the barrel, of a tapered sleeve slidable upon the muzzle, 90 a pair of opposite jaws connected to the rear end of the sleeve and having their rear ends received within the space between the magazine and the barrel, an intermediate cross-bar connecting the jaws and slidable between 95 the magazine and the barrel, a stop-shoulder upon the rear end of the sleeve and located between the barrel and the magazine, and a collar or ring rotatable upon the outer end of the magazine and having its inner end inclined or beveled to form a cam edge located in the path of the stop-shoulder on the sleeve. 100

In testimony that I claim the foregoing as my own I have hereto affixed my signature in the presence of two witnesses.

JAS. C. BROYLES.
